(57) **CLAIM**

The ornamental design for a food processing apparatus, as shown and described.

DESCRIPTION

The patent or application file contains at least one drawing executed in color. Copies of this patent or patent application publication with color drawing(s) will be provided by the Office upon request and payment of the necessary fee.

Figure 1.1 is a top, rear perspective view of a food processing apparatus showing the new design;

Figure 1.2 is a front view thereof;

Figure 1.3 is a right side view thereof;

Figure 1.4 is a rear view thereof;

Figure 1.5 is a bottom view thereof;

Figure 1.6 is a top view thereof;

Figure 1.7 is a front, right side perspective view thereof; and

Figure 1.8 is a left side view thereof.

In the drawings the portions shown in the color red form no part of the claimed design.
